UNITED STATES PATENT OFFICE.

THOMAS O'BRIEN, OF BROOKLYN, NEW YORK.

LAMP.

1,085,155.

Specification of Letters Patent.

Patented Jan. 27, 1914.

Application filed December 4, 1912. Serial No. 734,965.

To all whom it may concern:

Be it known that I, THOMAS O'BRIEN, a citizen of the United States, residing at Brooklyn, in the county of Kings and State of New York, have invented certain new and useful Improvements in Lamps; and I do hereby declare the following to be a full, clear, and exact description of the invention, such as will enable others skilled in the art to which it appertains to make and use the same.

This invention relates to lamps and stoves and more particularly to that type using wicks and has for an object to provide means for exposing more or less of a portion of the wick so as to increase or decrease the flame.

A further object of this invention is to provide a simple device having the least number of parts using a wick which does not vary its vertical movement with respect to the reservoir of the lamp or stove.

A further object of this invention is a provision of a removable tip which when charred may be thrown away to avoid the trimming of the wick.

A further object of this invention is a provision of a wick which terminates at the bottom of the reservoir at all times so as to absolutely drain the reservoir.

A further object of this invention is the provision of an adjusting means for exposing more or less of the wick which adjusting means serves as a support for a globe or chimney.

A further object of this invention is the provision of an adjusting means for exposing more or less of the wick which adjusting means is rotatable to vary its relation with respect to the wick.

Further objects will be apparent from the following specification, appended claims and drawings, in which.

Figure 1 is a vertical sectional view through a lamp constructed in accordance with this invention, Fig. 2 is a horizontal sectional view as on the line 2-2 of Fig. 1, and Fig. 3 is a similar view on the line 3-3 of Fig. 1.

This invention provides for a stationary wick having the lower end thereof terminate at the bottom of the reservoir at all times so as to drain the entire contents of the reservoir and has a further provision for trimming of the wick as by a removable tip which may be replaced when charred.

In retaining the wick in stationary position it is necessary that some vertically adjustable means be provided to expose more or less of the wick so as to diminish or intensify the flame.

Referring to the drawings there is shown a reservoir 10 having the central air passage 11 which terminates above the reservoir as shown and is provided with a perforated hood 12. The top of the reservoir is formed to provide an opening 13 which is internally threaded to receive the externally threaded sleeve 14 which sleeve has its interior spaced from the air duct 11 to admit the wick 15 which terminates near the top of the air duct 11 and at the bottom of the reservoir 10 so that as long as any oil remains within the reservoir, the wick exerts its absorbing action and conducts the oil to the top. Instead of igniting the upper end of the wick 15 so that the same will eventually become burned or charred and therefore necessitate trimming, I provide a removable tip 16 of a similar diameter and type to the wick but of a comparatively short length so that as this section becomes charred or burned it may be removed and thrown away. The hood 12 is shaped so as to form a covering over the end of the wick 16 to prevent that portion of the wick from burning and this hood is further provided with a depending flange 17 which fits within the air duct 11. The air passages 18 through the hood are disposed so as to direct currents of air within the annular flame to promote combustion and enlarge the flame.

The sleeve 14 is rotatable in the threaded opening 13 so that rotation thereof in one direction causes a downward motion of said sleeve whereas rotation in the opposite direction raises the sleeve so as to cover more or less of the tip 16. The sleeve is provided with a flange 19 which terminates in a bead 100 for manipulation thereof and this flange is also provided with a series of perforations 20 to admit air between the globe 21 and the tip 16 to support combustion.

The operation of the lamp is obvious and it is clearly seen that rotation of the disk 14 in one direction covers the tip 16 so as to extinguish the flame while rotation in the other direction exposes the wick so that the same may be lighted and there is an adjustment for any range of exposure of the wick.

Modifications may be made within the

scope of this invention and I do not restrict myself to the form shown which is submitted for illustrative purposes only.

Having thus described my invention, I claim:

1. In a burner, a reservoir, a central duct therein, said central duct rising above the level of the reservoir, a textile sectional wick about the central duct, a sleeve carried by said reservoir, said sleeve having adjustment with said reservoir by circumferential movement, an annular flange carried by said sleeve and a cap carried by said central duct for said duct and sectional wick.
2. In a burner, a reservoir, a central duct therein, said central duct rising above the reservoir, a stationary wick in said reservoir about said central duct, a longitudinally movable sleeve in engagement with and about said wick, said sleeve having direct threaded engagement with said reservoir, a cap carried by said central duct and a removable section of textile wick superimposed on said stationary wick.
3. In a burner for lamps or stoves, a reservoir a stationary sectional wick about said central duct, a sleeve having threaded connection with said reservoir and having longitudinal movement with respect thereto, said sleeve surrounding said wick sections, a perforated flange carried by said sleeve, a chimney carried by said flange outside of the perforations and a cap carried by said central duct said cap overhanging said duct to form a shoulder over said wick sections and said cap having a perforated wall in alignment with the exterior of said wick sections.
4. In a burner, a movable sleeve serving as a closure for a reservoir and as a regulator for exposing a wick, said sleeve comprising a tubular member having a smooth inner surface, a perforated flange formed on the periphery thereof spaced from one end, a bead formed on the periphery of said flange, said tube having a portion of its length cut in screw threads, and said tube being plain for an interval between the screw threads and the opposite end thereof.

In testimony whereof I affix my signature in presence of two witnesses.

THOMAS O'BRIEN.
